UNITED STATES PATENT OFFICE.

GEORGE CARR, OF PATERSON, NEW JERSEY.

ARTIFICIAL TOOTH-CROWN AND BACKING.

1,035,688.

Specification of Letters Patent. Patented Aug. 13, 1912.

Application filed March 13, 1912. Serial No. 683,460.

To all whom it may concern:

Be it known that I, GEORGE CARR, a citizen of the United States, residing at Paterson, in the county of Passaic and State of New Jersey, have invented certain new and useful Improvements in Artificial Tooth-Crowns and Backings, of which the following is a specification.

This invention relates to certain new and useful improvements in artificial tooth crowns and backings therefor, and the invention consists of the improved tooth crown and backing which I will hereinafter describe and point out in the claims.

15 A leading object of the invention is to provide artificial teeth with all porcelain cusps for bicuspids and molars and an all porcelain tip for the anteriors (cuspid, laterals and centrals) and to so fashion these 20 teeth that they are readily removable during construction and interchangeable in case of necessity, said teeth being capable of use with a backing or plate which is fashioned to conform to corresponding portions of any 25 of the teeth of a given mold.

In the accompanying drawing forming part of this specification, and in which similar reference characters indicate like parts in the several views;—Figure 1 is a perspective view of an artificial tooth crown embodying my invention and fashioned to receive the backing or plate. Fig. 2 is a perspective view of the backing or plate for the tooth crown of Fig. 1. Fig. 3 illustrates a 30 tooth crown fashioned slightly modified from the construction shown in Fig. 1. Fig. 4 is a backing or plate designed for use with the tooth crown of Fig. 3. Fig. 5 is a cross-section of the tooth crown shown in Fig. 1 35 with the backing plate attached. Fig. 6 is a sectional view showing an anterior tooth crown constructed according to my invention.

In the drawing I have illustrated in Fig. 45 6, an anterior tooth crown and in Figs. 1 and 3, a molar and it will be understood that the scope of the invention includes bicuspids, molars, etc., and that the two instances shown may be considered as illustrative of 50 any and all kinds and sizes of teeth.

The tooth crown, A, is of porcelain and is molded and baked in the manner well known in this art, and, therefore, not necessary to be described herein. A substantial portion 55 of the rear of the base of the tooth is re-

moved, but sufficient of the front remains to give the tooth the desired strength and appearance and to leave all porcelain cusps, for bicuspids and molars have occlusal surfaces of all porcelain; the six anteriors have all 60 porcelain tips as well as an all porcelain labial surface.

The cut-away or reduced base portion of the tooth is ground down on two opposite corners in lateral planes to form the transversely inclined surfaces, a, b. These inclined surfaces may be at any desired angle crosswise of the tooth and I have found in practice that the angle of 45° is well suited for my purpose, although I do not restrict 70

the invention to this or any specific angle. Whatever the angle given the opposite sides of the reduced base portion of the tooth, said angle should be common to all teeth of a given mold, including bicuspids, molars, 75 etc., in order that the teeth may be readily renewable and interchangeable and used in connection with a backing of angular cross-section, and which angle is similar to that which is given the base of the tooth, and 80

which is represented at a, b; in other words, the angular surfaces, a, b, will be common to teeth of all widths and lengths which will make any given mold interchangeable, in case of necessity, without removal of the 85 abutment or bridge, as an accident, or where the shade of tooth decided on was found to be incorrect; also, if a tooth is found to be too long, or too short, after bridge or crown work has been constructed. Also allows the 90 removal of crown while soldering and does away with the possibility of checking the porcelain or changing the shade by passing porcelain through the fire.

The two inclined surfaces resulting from 95 the grinding of the upper corner portions of the reduced base part of the tooth may connect along a line which extends centrally from front to back of the tooth, thus giving the upper portion of this part of the tooth 100 a substantially widened V-shape in cross-section, as shown in Fig. 3; or, if desired, the cross-sectional shape may be modified to represent substantially a flattened V-form, in which case the two transversely inclined 105 surfaces will be connected by an intermediate flat surface, c, as shown in Fig. 1. In either of the instances shown, the cutting down of the base results in the formation of a vertical shoulder or wall, d, at the front 110

ends of the inclined surfaces, *a*, *b*, and back of this shoulder or wall and closer thereto than to the back end of the tooth, a hole, *e*, is made vertically or at an angle 5 into the tooth, said hole being of desired depth for a retaining pin, which I will hereinafter describe, and said hole being positioned in the center of the arch formed by the inclined surfaces, *a*, *b*.

10 In connection with the tooth fashioned as hereinbefore described, I use a backing, *B*, as illustrated in Figs. 2 and 4, said backing being formed of metal of a character suitable for dental purposes and being bent at 15 two opposite sides to form the laterally extending inclined planes or wings, *f*, *g*, and being further bent to form a vertical flange, *h*, at one end thereof. The backing is thus given an arched form and the cross-section 20 of the arch will correspond to the transversely inclined surfaces, *a*, *b*, of the tooth, so that the tooth will readily conform to the backing, said backing having a fixed pin, *l*, adapted to enter the hole, *e*, in the tooth, and 25 correctly center said tooth, and the vertical flange, *h*, being adapted to seat against the corresponding shoulder or wall, *d*, formed on the tooth. I prefer that the fixed pin, *l*, shall have its upper end projecting above 30 the crown of the arch of the plate shown in Fig. 4 and also in the flat middle portion of the plate shown in Fig. 2. The projection may be about 3/4 the height of the vertical flange, *h*, and this projection gives added 35 strength to the plate, as in practice solder fills in all the space up even with the top of the wall when the crown or bridge is complete. The pin, therefore, braces and strengthens the plate at the point where 40 great strength is desired.

From the foregoing it will be apparent to those skilled in this art that as all the 45 crowns of a common mold, after baking, are ground down to form the laterally-inclined surfaces, *a*, *b*, in either of the instances shown, or in any other of a like character, and as the backing is fashioned with corresponding inclined surfaces, said crowns will accurately fit the same backing and accordingly the teeth are interchangeable; they require less solder in construction work; they are stronger at the points heretofore regarded as weakest in other crowns; the backing will be of uniform shape, being struck 50 up from a single die, and hence, accurately fit the molds; the teeth are more sanitary

and so far as I know have the only anterior crowns which are interchangeable.

Having thus described my invention what I claim as new and desire to secure by Letters Patent is:—

1. An artificial tooth cusp having a base, the rear portion of which is reduced in height to form a vertical shoulder on the rear of the cusp, said reduced rear portion 65 being ground along two opposite corner portions to form transversely diverging surfaces.

2. An artificial tooth crown having a base, the rear portion of which is reduced in height to form a vertical shoulder on the rear of the cusp, said reduced rear portion being ground along two opposite corner portions to form transversely diverging surfaces, and a backing bent to form angular 75 sides conforming to and seating upon the diverging surfaces of the base.

3. An artificial tooth crown having a cut-away base ground along two opposite corner portions to form transversely diverging surfaces, and a backing bent to form angular 80 sides conforming to and seating upon the diverging surfaces of the base, said crown having a vertical shoulder on its rear and said backing being formed with a vertical flange 85 to seat against said shoulder.

4. An artificial tooth crown having a cut-away base ground along two opposite corner portions to make the base substantially V-shaped in cross-section, said base having a 90 hole, and a backing bent to conform to and fit the cross-section of the base and having a pin to engage the hole therein.

5. An artificial tooth crown having a base, the rear portion of which is reduced in 95 height to form a vertical shoulder on the rear of the cusp, said reduced rear portion being ground along two opposite corner portions to make the base substantially V-shaped in cross-section, said base having a 100 hole, and a backing bent to conform to and fit the cross-section of the base and having a pin to engage the hole therein, said pin also projecting above the upper surface of the 105 backing.

In testimony whereof I affix my signature in presence of two witnesses.

GEORGE CARR.
